MULTIPLE SOLUTION STIRRER

Harry D. Brown, Grand Junction, Colo.

Application May 9, 1958, Serial No. 734,171

1 Claim. (Cl. 259—67)

This invention relates to a solution stirring device more particularly for use in chemical laboratories, and has for its principal object the provision of a simple and highly efficient multiple stirring device for simultaneously stirring a plurality of solutions from a single power source, by means of which solution containers such as laboratory beakers can be quickly, easily and safely placed in or removed from stirring position while the stirrer is in operation.

Another object of the invention is to provide means for detachably supporting a conventional glass laboratory stirring rod at an angle to the axis of stirring rotation so as to provide a maximum stirring action without it being necessary to bend or deform the rod.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a top view of the improved multiple stirring device;

Fig. 2 is a front view thereof;

Fig. 3 is a right side view thereof;

Fig. 4 is an enlarged, fragmentary, detail view illustrating a stirring rod clamp as employed in the improved multiple stirring device; and

Fig. 5 is a top view of the rod clamp, taken on the line 5—5, Fig. 4.

The improved multiple stirrer is assembled in a supporting frame which, as illustrated, comprises two end frame members 10 and 11 which support an elongated top member 12. The end frame members 10 and 11 are maintained in vertical spaced-apart relation by means of an elongated table member 13 which extends between the side members at approximately one third their vertical height. A hold-down strip 14 is secured to and extends longitudinally of the table member 13 and is spaced from the latter by means of uniformly separated spacers 15.

A plurality of flat, elongated, beaker shelves 16 are arranged to slide transversely of the table member 13 between the spacing members 15. The beaker shelves 16 are maintained in a horizontal plane by means of the hold-down strip 14, and each is preferably provided with a finger button 17 to facilitate its being drawn forwardly or pushed back on the table member 13.

A horizontal (preferably square) bearing bar 18 extends between the side frame members 10 and 11 above and forwardly of the table member 13. The bearing bar is secured at its extremities in the side frame members by means of suitable set screws 19. A plurality of vertical spaced-apart, tubular shaft bearings 20, corresponding

2

in number to the number of shelves 16, extend through and are supported by the bearing bar 18. A relatively short stirring shaft 21 is rotatably mounted in each shaft bearing 20 in vertical alignment with the longitudinal center line of each shelf. Each stirring shaft 21 terminates at its upper extremity in a grooved belt pulley 22 and its lower extremity in a rod clamp 23.

The rod clamps are formed from sheet metal bands which are folded in a U-shape about the stirring shafts, 10 and secured thereto by means of key pins 24. Each of the folded blanks extends radially from its stirring shaft to form two opposed clamping ears which may be clamped together by means of a suitable clamp bolt 26. An inclined, semi-cylindrical socket 25 is formed in each clamping ear which cooperates to form a rod channel to receive a glass laboratory stirring rod 27. The axis of each of the rod channels is positioned at an acute angle to the axis of the adjacent stirring shaft so as to place the glass stirring rod in an eccentric, inclined stirring position to obtain a maximum stirring effect from the conventional straight glass rod.

The stirring action is obtained from an electric motor 29 mounted on the top member 12. The motor's shaft indicated at 30 extends downwardly from the motor to 25 drive a double grooved motor pulley 31 from which endless transmission belts 32 are trained about all of the pulleys 22 of the stirring shafts 21.

The solutions to be stirred are placed in containers such as the laboratory beakers illustrated at 28. The 30 beakers are lifted upwardly about the stirring rods 27 with the shelves 16 in the "push-back" position. The shelves are then drawn forwardly beneath the beakers to support the latter during the stirring operation. A beaker can be removed without stopping the motor 29 by 35 simply supporting it on one hand while the shelf is pushed-back and then lowering it from the stirring rod.

While a specific form of the improvement has been described and illustrated herein, it is to be understood that the same may be varied within the scope of the appended claim, without departing from the spirit of the invention.

Having thus described the invention, what is claimed and desired secured by Letters Patent is:

A multiple solution-mixer comprising: two upstanding end members; an elongated bearing bar extending horizontally between and supported by said end members; a plurality of vertical spaced-apart shaft bearings mounted on said bearing bar; a stirring shaft mounted in each bearing and extending downwardly therefrom; a clamp on each stirring shaft a stirring element mounted in and depending from each clamp at an acute angle to the axis of the stirring shaft; an elongated table member secured at its extremities to said end members and extending between the latter below and rearwardly of said bearing bar; a plurality of spaced-apart flat shelves supported on and arranged to slide horizontally and transversely of said table member so that they may be drawn forwardly to a position below said stirring elements; a hold-down strip slidably securing said shelves on said table member and means for simultaneously rotating all of said shafts; said means for simultaneously rotating all of said shafts comprising: an elongated top member secured on and extending between said end members above said bearing bar; a motor supported on said top member; a motor shaft driven by and extending downwardly from said motor; a driven pulley on each of said mixer shafts; a drive pulley on said motor shaft; and an endless belt trained about all of said pulleys so that they will be driven in unison.
